METHOD OF CONSTRUCTING SUBWAYS AND
LIKE UNDERGROUND STRUCTURES

Ralph H. Burke, Evanston, Ill.

Application May 14, 1938, Serial No. 207,897

10 Claims. (Cl. 61—44)

The present invention relates to the construction of subways and other underground structures, and contemplates a new mode of operation that includes first erecting the retaining walls that 5 constitute the sides of the proposed subway, then roofing over the space between such walls to form a roadway as well as a ceiling for the subway, so that the construction of the subway may be carried on with little if any interference with the 10 use of the street or roadway for traffic. The retaining walls may be located at or near the lines of the curbs, and by then roofing over the space between such walls a roadway may be provided for traffic while at the same time the material 15 between the side walls and under the roof is being excavated and the subway is being completed in other respects.

It is old in the art to build underground retaining walls by first sinking a vertical shaft and 20 then excavating the earth and building the wall in sectional courses, beginning at the lowermost course of the wall and constructing each super-jacent course or section upon a subjacent course or section that has been previously completed. In 25 such constructions, however, the first wall section or course is completed before the next wall section tunnel is excavated, and it is therefore necessary in such cases to carry the concrete for each course down through the shaft and into each 30 tunnel, the filling beginning at the far or blind end of the tunnels, requiring the expenditure of much time and labor in placing the concrete. With such method, also, the material excavated from each of the upper tunnels must be removed 35 through the tunnel in which the excavating is then being carried on, which often necessitates the excavation of a larger tunnel than is needed to accommodate the concrete wall desired, and also requires the use of forms to construct the concrete wall of the dimensions desired, all of which 40 makes for crowded working conditions in the tunnel and therefore loss of time in the excavating operations. It is also old in the art to excavate the earth between the walls before roofing 45 over the space between them, and to place in such excavation forms that are suitably braced from below on to which the concrete of the roof section of the subway is poured.

The present invention has for its principal object 50 to provide a simple and safe method of constructing retaining walls, supporting piers and the like, and the roofs of subways and other underground structures, whereby the time and labor required in the excavating operation and 55 the filling with concrete to form the same will

be reduced to a minimum, so as to make the construction of such retaining walls and roof inexpensive as compared to the prior methods of construction.

In constructing a subway, or like underground structure, by my improved method, I first sink a vertical shaft to a point level with or below the lowermost section of the wall to be constructed. Then, beginning at the lower end of the shaft, I excavate a tunnel of suitable height, and of about 5 the width of the thickness of the proposed wall. This lowermost tunnel is of such size and shape as to provide working room for transporting the earth excavated therefrom and from the superposed tunnels subsequently excavated. Since the 10 base section of the proposed wall is ordinarily wider than the upper portions, the lowermost tunnel is about the width of the proposed base section. The length of this tunnel will correspond 15 with the length of the wall section that is to be built by operating from the shaft. In extending this lowermost tunnel its sides are lagged or lined with side plates and said plates are braced or stiffened with strips or angles secured to upper and lower margins thereof. Also secured to the 20 side plates adjacent their upper margins are cross strips or braces spaced apart longitudinally of the tunnel. Loosely supported by the stiffening strips at the upper margins of the side plates are removable steel plates forming a temporary solid 25 roof for the lowermost tunnel to retain the earth above it. After completing the excavation of the lowermost tunnel, still operating from the shaft, the next higher tunnel is excavated, the plates forming the roof of the lowermost tunnel being 30 successively removed as the excavating progresses, thus allowing the material excavated from the upper tunnel to drop down between the cross strips into the lowermost tunnel, from which it is removed through the shaft. The sides of the 35 second tunnel are lagged and braced in a manner similar to those of the first tunnel, and in addition the lower margins of the side plates of the second tunnel are secured to the upper margins of the side plates of the lower tunnel, spaced-apart cross strips or braces are connected between 40 the upper margins of the side plates of the second tunnel, and removable steel plates are placed to 45 form a solid roof for such tunnel, as in the case of the lowermost tunnel. After digging the 50 second tunnel, the next higher one is excavated in the same way, in each case the excavated material being allowed to drop into the lowermost tunnel for removal therefrom through the shaft, and so on until the full height of the wall is 55

reached. Of course, in the case of a topmost tunnel which would reach the street level, if preferred the material dislodged could be thrown out into the street instead of being allowed to 5 drop through the several tunnels into the bottom one. After the several tunnels have been completely excavated concrete is poured into them through pipes extending from the ground surface into the uppermost tunnel, or extended into 10 the lower tunnels, as may be desired, said pipes being spaced apart at suitable distances along the length of the proposed wall, and the concrete will pass through the pipes or the open upper portions of the several tunnels in the filling operation, so that the lowermost tunnel will be filled 15 first, and then the remaining tunnels in succession, as will be readily appreciated. If the uppermost tunnel reaches the ground surface or street level, the pipes may be dispensed with and 20 the concrete poured directly into the several tunnels by the usual method to fill them in succession. Tunnels may be extended from the shaft in more than one direction, so that by sinking one shaft a considerable length of wall or walls can 25 be formed. Similarly, a shaft may be provided at each end of a proposed wall section, with the work progressing towards the center of said section from the two shafts.

In the accompanying drawings I have shown 30 one form of means for carrying out my improved method. As there illustrated:

Figure 1 is a longitudinal vertical sectional view through a shaft and three partially completed superposed tunnels, showing the successive steps 35 of excavating and forming the tunnels; also one of the concrete receiving pipes extending between the upper tunnel and the ground surface;

Figure 2 is a vertical cross-sectional view taken on the line 2—2 of Figure 1, and showing in addition in dotted lines two adjacent parallel retaining walls;

Figure 3 is a vertical cross-sectional view on an enlarged scale showing the cross strips or braces interposed between the upper and lower ends of 45 the side plates at opposite sides of the tunnel;

Figure 4 is a fragmentary vertical cross-section on an enlarged scale, showing the means for connecting the side plates of a lower tunnel to the side plates of the next higher tunnel, and the 50 means for connecting the cross braces to the side plates;

Figure 5 is a vertical cross-sectional view showing a subway structure comprising three retaining walls and a roof supported thereon constructed in accordance with my improved method and before the earth between the retaining walls and below the roof has been excavated; and

Figure 6 is a vertical cross-sectional view similar to Figure 5 showing the subway after the 60 excavation of the earth between the walls and below the roof, and the laying of the floor.

In carrying out my improved method, I first construct two side walls, and an intermediate wall when one is required, and each of such walls is 65 constructed by sinking a vertical shaft 6 down to a point level with or below the foot of the lowermost section of the proposed wall, and the side walls of the shaft may be lined with a plurality of side plates such as those shown at 7 in Figure 1, 70 if desired. Then a tunnel 8 is excavated, commencing at the bottom of the shaft and extending along the line of the proposed wall, and as the excavating progresses a plurality of side plates 9 are placed along the sides of the tunnel to prevent 75 the earth adjacent thereto from falling into

the tunnel, as is usual in tunnel construction. The plates 9 in the lowermost tunnel extend from the top to the bottom of the tunnel, and in the preferred construction said side plates flare or diverge outwardly from top to bottom as shown 5 in Figures 2 and 3, so that the bottom portion of the tunnel is wider than the top portion thereof. The purpose of such construction is to provide more room for the workmen engaged in removing the material from the tunnel and also to provide for the use of small dump cars, such as shown at C in Figure 3, that are usually used in tunnel construction. The side plates 9 may be joined together by flanges or otherwise to form a continuous lining. If desired, after all of the 10 tunnels have been completed and before the concrete is poured thereinto, vertically arranged side plates may be inserted in lieu of the diverging plates 9, or the plates 9 may be left in place and 15 vertically arranged plates or forms of other desired shape may be inserted on the inner sides thereof in addition thereto, to form the concrete 20 wall of any desired shape or dimension.

An angle bar 10 is secured to the inner face of each of the side plates 9 adjacent the upper 25 margin thereof by welding or otherwise suitably securing one flange 11 of said bar to said plate, the other flange 12 of the angle bar extending inwardly from said plate in a horizontal plane for a purpose to be hereinafter described. The upper 30 ends of the side plates 9 at opposite sides of the tunnel are braced and held apart by spaced-apart cross strips or braces 13 that are preferably in the form of steel rods or bars having their outer ends reduced in diameter as shown at 14 and inserted 35 in holes 15 provided therefor in the flanges 11 of the angle bars 10 as best shown in Figure 4. Removable steel plates 16 are placed loosely on the angle bars 10 to form a temporary roof for the lowermost tunnel and to retain the earth above 40 such lowermost tunnel until said earth is excavated in forming the next higher tunnel. These removable plates 16 provide a footing for the workmen in excavating the next higher tunnel, and are removed in succession as such excavation 45 proceeds. The brace rods 13 are preferably formed in two sections connected together by a turnbuckle to facilitate the insertion of the ends 14 of the rods in the holes 15 and to adjust them tightly in place, as will be readily appreciated. 50 It is to be understood that any desired number of such braces may be used as are necessary to resist the pressure of the earth on the sides of the tunnel, so long as they are spaced apart sufficiently to permit the material excavated from the next higher tunnels, and the concrete that is 55 poured in from above when the tunnels are completed, to drop therebetween into the lower tunnels.

As shown in Figure 3, preferably an angle bar 60 17 is secured to the inner face of each of the side plates 9 adjacent its lower margin in a manner similar to that in which the angle bars 10 are secured to the upper margins of said plates, and the lower ends of the side plates 9 at opposite sides of 65 the tunnel are braced and held apart by lower cross-braces or rods 18, similar to the upper brace rods 13, that have their reduced outer ends inserted in holes provided therefor in the flanges of the angle bars 17.

After the first tunnel has been completed to any 70 desired or convenient distance from the shaft, and before concrete is placed therein, the excavating of the second tunnel 23 is commenced, starting from the shaft. As the excavating of the tunnel 75

23 progresses the removable steel plates 16 forming the solid roof of the lower tunnel 8 are removed, allowing the material excavated from the tunnel 23 to drop between the cross strips or 5 braces 13 into the lowermost tunnel, from which it is removed from the shaft. During this work the sides of the tunnel 23 are lined with steel side plates 24 similar to the side plates 9 of the lowermost tunnel except that the plates 24 are preferably vertically arranged as shown. These 10 plates 24 are also preferably joined together by flanges or otherwise to make a continuous lining. Each of the side plates 24 adjacent its lower margin is provided with an angle bar 25 having one 15 flange 26 thereof secured to said plate and its other flange 27 extending inwardly from said plate in a horizontal plane in a position just above the flange 12 of the angle bar 10 at the upper end of the side plate 9 of the lower tunnel, and the angle 20 bars 10 and 25 are secured together by means of a bolt 28 extending through aligned openings in the flanges 12 and 27 of said angle bars, respectively, said bolt being held in position by a nut 29 threaded thereon.

25 As shown in Figures 3 and 4, the lower ends of the side plates 24 at opposite sides of the tunnel 23 are braced and held apart by spaced apart cross braces 31 similar to the cross braces 13 and 17, and have their reduced outer ends 32 inserted 30 in holes 33 provided therefor in the flanges 26 of the angle bars 25, as shown in Figure 4.

The upper ends of the side plates 24 at opposite sides of the tunnel 23 are held spaced apart in proper position by means of spaced cross braces 35 35 (Figure 1) that are similar in all respects to the cross braces 13 and similarly connected to the angle bars 36 at the upper ends of the side plates 24. Removable steel plates 37 are placed on said angle bars 36 to form a temporary roof for the 40 tunnel 23, similar in all respects to the plates 16 which form the temporary roof of the tunnel 8.

After the second tunnel has been completed, the next succeeding higher tunnel 38 is excavated, commencing at the shaft, and as the excavating progresses the material dislodged is allowed to drop between the braces 35 and 31, and 45 13 of the tunnel sections 23 and 8, respectively, to the bottom of the lowermost tunnel 8, from which the material is removed through the shaft. This tunnel 38 is lined with side plates 39 similar 50 to the side plates 24 and cross braced as shown at 41-42 in Figure 1 in the same manner as the side plates 24 as above described, and removable steel plates 43 are placed on the angles 44 at the upper 55 ends of the side plates 39 to form a roof for the tunnel 38, in the same manner as plates 16 and 37 are used in tunnels 8 and 23, respectively.

It is well to point out that the excavation of each of the upper tunnels may be started as soon 60 as the next lower tunnel has been excavated a short distance, so that the work of excavating the several tunnels may be concurrent to a large extent, as will be readily understood.

In cases where the uppermost tunnel section 38 65 does not reach the ground surface, as in the illustrated construction, I provide means for filling the tunnel sections with concrete from the ground surface, and such means comprises a plurality of pipes 44, one of which is shown in Figure 1, 70 that are spaced apart at suitable distances along the length of the upper tunnel and extend from the ground surface into said tunnel. The concrete for filling the tunnels is poured into said pipes and drops down between the several spaced 75 brace members of the tunnels, the several tunnels

being filled in succession, beginning with the lowermost tunnel. If desired, pipes 44 may be extended into the tunnels 8, 23, and 38 by extension pipe sections 45, as shown in dotted lines in Figure 1, such extension pipe sections being removed as the placing of concrete proceeds. In cases where the uppermost tunnel reaches the ground surface, the pipes 44 are dispensed with and the material is poured directly into the uppermost tunnel, and distributed in the tunnels by the usual construction method.

One advantage derived from my method of constructing retaining walls for tunnels is that by providing the spaced apart braces in the several tunnels, reinforcing members that extend 15 through all of the tunnels may be introduced before the concrete is poured into the tunnels, whereby the finished wall will be properly strengthened and reenforced from top to bottom.

The method of constructing retaining walls outlined above is particularly advantageous in building subways under city streets, as, by the method described, the operation of building each wall may be confined to a narrow space at one side 20 of the roadway without the necessity of digging up the whole street or half of the street as the work progresses, thereby reducing interference with traffic to a minimum.

After the side walls, and the intermediate wall 30 if one is required, have been completed, as above described, the space between such walls is roofed over. In this operation the earth between the ground surface or street level and above a plane passing through the upper surfaces of the retaining walls is excavated, and concrete is then poured into such excavation in the usual manner to form a roadway between the walls as well as the roof of the subway. This is done before the earth between the walls is removed, so that such earth supports the concrete that forms the roof while the concrete is being poured. In Figure 5 I have illustrated a subway construction comprising two side retaining and supporting walls 47 and 48 and a centrally disposed supporting wall 49 on which a roof 51 formed in the manner above described is supported. After the roof has been completed, the earth between the walls 47 and 49 and 48 and 49 and below the roof 51 is excavated down to a point in line with the lower ends of the walls 47, 48, and 49, and concrete is then laid between the several walls to form the floor sections 52 and 53 as shown in Figure 6.

This method of construction is particularly 55 advantageous in building subways under city streets since it provides a practical means of constructing the side walls of the subway before the main excavating of the subway is begun. The walls having thus been first constructed, the roof 60 of the subway may be constructed at street level, resting upon the previously constructed walls, after which the excavating necessary for completing the subway may be proceeded with beneath the completed roof and between the completed walls, in utmost safety, without interference with street traffic and without the inconvenience of using temporary bracing to hold the sides or roof of the excavation. It is apparent that the procedure above described, which is made 65 possible by the use of my method of constructing concrete retaining walls described herein, obviates the necessity of constructing a temporary street deck structure under which the work of excavating and constructing the subway may be 70 75

carried on, and therefore provides for constructing subways at a higher level than heretofore, thus effecting a substantial saving in the total amount of excavating work required for the subway; and obviating entirely the use of back filling that is usually required above the roof of the subway to fill to the required street grade and saving entirely the repaving of the street after construction of the subway. The method is of 5 further advantage in the operation of the subway after completion, in that it allows construction of the subway at a higher level than was heretofore practicable, minimizing the steps necessary for the users of the subway to take in descending to and ascending from the platform 10 levels in the subway.

I claim:

1. The method of constructing concrete retaining walls for subways, underground structures, and the like, which comprises sinking a 20 shaft to or below the level of the foot of the wall to be constructed, excavating a tunnel beginning at said shaft, excavating similar successively higher tunnels beginning at said shaft along the line of and over said first tunnel, whereby as said 25 tunnels are successively excavated the material therefrom will drop down into said first tunnel, removing the material excavated from successively higher tunnels through said lowermost 30 tunnel, and filling said tunnels in succession, commencing with the lowermost tunnel, from above with concrete.

2. The method of constructing a plurality of superposed tunnels for the purpose of building a concrete retaining wall, which comprises sinking a 35 shaft to or below the level of the foot of the proposed wall, excavating the lowermost tunnel beginning at said shaft, providing a sectional removable ceiling for said tunnel, successively excavating and constructing one or more like superposed tunnels over and in line with said lowermost tunnel, meanwhile progressively removing such ceilings, so that the material excavated from 40 said superposed tunnels is allowed to drop down into the lowermost tunnel, and removing the material excavated from said superposed tunnels from 45 said lowermost tunnel through said shaft.

3. The method of constructing concrete retaining walls for subways and the like, which comprises sinking a shaft to or below the level of the 50 foot of the wall to be constructed, excavating a tunnel beginning at said shaft, providing a sectional removable ceiling for said tunnel, excavating and constructing similar successively higher tunnels beginning at said shaft along the line of and over said first tunnel, meanwhile progressively removing such ceilings, whereby as said 55 tunnels are successively excavated the material therefrom will drop down into said first tunnel, removing the material excavated from successively higher tunnels through said lowermost 60 tunnel, and filling said tunnels in succession from above with concrete.

4. The method of constructing concrete retaining walls for subways and the like, which comprises sinking a shaft to or below the level of the 65 foot of the wall to be constructed, excavating a tunnel beginning at said shaft, providing a sectional removable ceiling for said tunnel excavating and constructing similar successively higher tunnels beginning at said shaft along the line of and over said first tunnel, meanwhile progressively removing such ceilings, whereby as said 70 tunnels are successively excavated the material therefrom will drop down into said first tunnel,

removing the material excavated from successively higher tunnels through said lowermost tunnel, providing an opening between the uppermost tunnel and the ground surface, and filling all of said tunnels in succession, commencing with the 5 lowermost tunnel, with concrete poured through said opening.

5. The method of constructing concrete retaining walls for subways and the like, which comprises sinking a shaft to or below the level of 10 the foot of the wall to be constructed, excavating a tunnel beginning at said shaft, providing lining plates along the side walls of the tunnel, providing spaced apart cross braces between the upper ends of the lining plates at opposite 15 sides of said tunnel, providing a sectional removable ceiling for said tunnel, excavating and constructing successively higher tunnels beginning at said shaft along the line of and over the first tunnel in a manner similar to that of said 20 first tunnel, meanwhile progressively removing such ceilings, whereby as said tunnels are successively excavated the material therefrom will drop down between said cross braces into said first tunnel, removing the material excavated from 25 successively higher tunnels through said lowermost tunnel, and filling all of said tunnels, in succession, commencing with the lowermost tunnel, with concrete poured into said tunnels from above.

6. The method of constructing subways and like underground structures, which comprises forming two or more spaced apart retaining walls below the ground surface, each of which is constructed by sinking a shaft to or below the level 35 of the foot of the proposed wall, excavating the lowermost tunnel beginning at said shaft, providing a sectional removable ceiling for said tunnel, successively excavating and constructing one 40 or more like superposed tunnels over and in line with said lowermost tunnel, meanwhile progressively removing such ceilings, so that the material excavated from said superposed tunnels is allowed 45 to drop down into the lowermost tunnel, removing the material excavated from said superposed tunnels from said lowermost tunnel through said shaft, roofing over the space between said retaining walls to form a roof for the subway, and thereafter removing the material from between 50 said walls and below said roof.

7. The method of constructing subways and like underground structures, which comprises forming two or more spaced apart retaining walls below the ground surface, each of which is constructed by sinking a shaft to or below the level 55 of the foot of the wall to be constructed, excavating a tunnel beginning at said shaft, providing a sectional removable ceiling for said tunnel, excavating and constructing similar successively higher tunnels beginning at said shaft along the 60 line of and over said first tunnel, meanwhile progressively removing such ceilings, whereby as said tunnels are successively excavated the material therefrom will drop down into said first tunnel, removing the material excavated from 65 successively higher tunnels through said lowermost tunnel, filling said tunnels in succession from above the concrete, roofing over the space between said retaining walls to form a roof for the subway, and thereafter removing the material from 70 between said walls and below said roof.

8. The method of constructing subways and other underground structures which comprises forming two or more spaced apart retaining walls below the ground surface, each of which is con- 75

structed by sinking a shaft to or below the level of the foot of the wall to be constructed, excavating a tunnel beginning at said shaft, excavating similar successively higher tunnels beginning at said shaft along the line of and over said first tunnel, whereby as said tunnels are successively excavated the material therefrom will drop down into said first tunnel, removing the material excavated from successively higher tunnels through said lowermost tunnel, and filling said tunnels in succession, commencing with the lowermost tunnel, from above with concrete, roofing over the space between said retaining walls to form a roof for the subway, and thereafter removing the material from between said walls and below said roof.

9. The method of constructing a subway under a street or roadway which comprises constructing a retaining wall below the ground surface along each side of the roadway, roofing over the space between said walls to form a pavement for the roadway and a roof for the subway, and thereafter excavating the earth from between said walls and below said roof. 5

10. The method of constructing a subway which comprises constructing a retaining wall below 10 the ground surface along each side of the subway, constructing a roof for the subway supported by said retaining walls, and thereafter excavating the earth from between said walls and below said roof.

RALPH H. BURKE.
